UNITED STATES PATENT OFFICE.

CHARLES M. NICHOLSON, OF BUFFALO, NEW YORK.

CARD GAME.

1,076,307.

Specification of Letters Patent.

Patented Oct. 21, 1913.

Application filed February 4, 1913. Serial No. 746,130.

To all whom it may concern:

Be it known that I, CHARLES M. NICHOLSON, a citizen of the United States, residing at Buffalo, in the county of Erie and State 5 of New York, have invented certain new and useful Improvements in Card Games, of which the following is a specification.

The invention relates to improvements in playing cards and particularly to a pack of 10 playing cards bearing characteristic data of distinctive value in the game for which the cards are adapted.

The main object of the present invention is the provision of a pack of cards, with 15 each bearing both a numeral and a letter, the numerals controlling and determining the value of the cards in playing, and the letters serving to permit the assemblage of the cards to form words or sentences.

20 The invention in the preferred form of detail will be described in the following specification, reference being had particularly to the accompanying drawings, in which—

25 Figure 1 is a view of the distinctive cards of the pack, the duplicates being omitted. Fig. 2 is a view showing the use of three cards to form a word. Fig. 3 is a similar view showing the cards arranged to form 30 a sentence.

The cards 1 which may be of any suitable material, of any size, and of any edge outline, are preferably similar in size, shape and material to the usual playing card. The 35 backs of the cards may be ornamented as desired, so long as they are similarly marked, and the faces of the cards, aside from the necessary data hereinafter described, may also be ornamented, though it is preferred 40 that they be left plain, as shown. On the face of the cards, at diagonally opposite corners is inscribed a letter of the alphabet as 2, and a numeral as 3. The distinctive cards are twenty-seven in number, bearing 45 respectively the twenty-six letters of the alphabet and the numerals from one to twenty-six, the numeral on a card corresponding to the sequence number in the alphabet of the letter borne by that card, 50 that is, the card bearing the letter A will have the numeral 1, and the card bearing the letter E will have the numeral 5, and so on. In addition to the alphabet cards there is another card bearing in place of a letter the

word and sign designating a "period," this 51 card bearing the numeral 27 and constituting the highest value card of the pack.

As previously explained, the cards are designed for forming words and sentences in playing, and for this purpose it is obvious 60 that duplicates of the cards described must be arranged in the pack. For example, and without intending any specific limitation in the particular number of duplicate cards used, I have found it convenient to use five 65 of the "E" cards; four of the "A," "I," "O," and "U" cards; three of the "F," "L," "M," "N," "P," "R," "S," "W" and "Y" cards; two of the "B," "C," "D," "G," "H," "J," "K," "T," "V," "Z" and 70 "period" cards; and one each of the "Q" and "X" cards. The pack thus constitutes seventy-two cards, though it is obvious that it may with equal efficiency be made to constitute any number, depending upon the 75 number of duplicates used.

In playing the game for which the cards are particularly designed, the numbers only have a playing value, taking rank in accordance with their number, making the 80 "period" card, which bears the number 27 the highest value card in the deck. The letters on the cards are to be used in forming words and sentences, the values of said words and sentences constituting the point 85 counting of the game, that is, the score. In playing the game among four or more players the cards are distributed in the usual manner among the players, one card being dealt at a time. Each player will then form 90 as many words and sentences as possible from the cards in his hand, and after the completion of this operation by all the players, one of the players, generally the dealer, will lead any one of the remaining cards 95 from his hand. The remaining players will play thereon a card from their hand and the card having the highest numerical value takes the trick. The player acquiring the 100 trick uses the cards gained to form additional words or sentences if possible after which he leads, as before, and the game is continued in this manner until the cards are exhausted. The "period" card having of course the highest value will take any trick, but cannot be played but once by any one player, this giving the players holding the 105 "period" card an opportunity to secure de-

sired letters to complete a word or sentence, but permitting them this advantage with only one trick. If cards of equal numerical value are played upon one trick, the player 5 of the first of such cards is entitled to the trick. When two or three are playing a certain number of cards are dealt to each player, as twelve, and after each trick, each player draws a card from the undealt portion 10 of the deck. In a partnership game, after leading against opposing hands has been completed, the partners' cards may be combined to build additional words, and words may be exchanged between partners 15 for the building of sentences. The point or scoring values depend upon the words or sentences, the value of a word being controlled by the number of syllables, and the number of points counted for a sentence being 20 governed by the number of words in that sentence. A sentence scores points both for a sentence and for the words therein. Any desired number of points for the respective scoring items may be used as agreed 25 upon.

From the above it will be seen that I provide a pack of cards which will not only furnish amusement but will prove highly instructive, having a wide range in the latter particular, as for example, a game may 30 be confined to words of a particular character, as for example, words used in baseball, geographical words, or others, and the

game in its general form can be played by any one.

Having thus described my invention, what I claim as new and desire to secure by Letters Patent, is:—

1. A pack of cards each bearing respectively one of the letters of the alphabet and also bearing a numeral corresponding to the particular sequence number in the alphabet of the letter borne by that card, the playing values of the cards being determined solely by their numbers, and the scoring value of the cards being predicated solely upon combinations of the letters borne by the cards. 45

2. A pack of cards each bearing respectively one of the letters of the alphabet and also bearing a numeral corresponding to the particular sequence number in the alphabet of the letter borne by that card, the playing values of the cards being determined solely by their numbers, and the scoring value of the cards being predicated solely upon combinations of the letters borne by the cards; and a final card having 50 any of the combinations of the letter cards. 55
